UNITED STATES PATENT OFFICE.

WILLIAM VICTOR JOHNSTON, OF THERMOPOLIS, WYOMING.

DESIGN FOR A POISON-BOTTLE.

No. 39,362.

Specification for Design.

Patented June 16, 1908.

Application filed March 25, 1908. Serial No. 423,281. Term of patent 7 years.

To all whom it may concern:

Be it known that I, WILLIAM VICTOR JOHNSTON, a citizen of the United States, residing at Thermopolis, in the county of Fremont and State of Wyoming, have invented a new, original, and ornamental Design for Poison-Bottles, of which the following is a specification.

The figure is a perspective view of the poison bottle showing my new design.

I claim:
The ornamental design for a poison bottle, as shown.

WILLIAM VICTOR JOHNSTON.
